UNITED STATES PATENT OFFICE.

ALBERT J. D. OHM, OF ASTORIA, NEW YORK, ASSIGNOR TO LION ELECTRIC APPLIANCE CO., INC., OF NEW YORK, N. Y., A CORPORATION OF NEW YORK.

DESIGN FOR A LIGHTING-FIXTURE CANOPY.

58,252.

Specification for Design. Patented June 28, 1921.

Application filed September 13, 1920. Serial No. 410,018. Term of patent 3½ years.

To all whom it may concern:

Be it known that I, ALBERT J. D. OHM, residing at 133 Steinway avenue, Astoria, in the borough of Queens, city and State of New York, and a citizen of the United States, have invented a new, original, and ornamental Design for a Lighting-Fixture Canopy, of which the following is a specification, reference being had to the accompanying drawing, forming part thereof.

Figure 1 is a side plan view, and Fig. 2 is a bottom plan view of a lighting fixture canopy showing my new design.

The drawing shows ornamentation on one-half only of the canopy, the other half having the same ornamentation.

I claim:

The ornamental design for a lighting fixture canopy, as shown.

ALBERT J. D. OHM.
